UNITED STATES PATENT OFFICE

IVAR L. LANGVAND, OF BARBERTON, OHIO, ASSIGNOR TO THE BABCOCK & WILCOX COMPANY, OF BAYONNE, NEW JERSEY, A CORPORATION OF NEW JERSEY

STEAM BOILER

Application filed September 19, 1928. Serial No. 306,851.

This invention relates to a water tube boiler in which provision is made for separating steam and water from each other while passing through the circulating tubes. The invention will be understood from the description in connection with the accompanying drawing in which Fig. 1 is a longitudinal section through an illustrative embodiment of the invention; Fig. 2 is a plan view of the same, and Fig. 3 is a section similar to Fig. 1 showing a modification.

In the drawing, reference character 1 indicates a steam and water drum of a water tube boiler of the Babcock & Wilcox type that is connected to the usual downtake headers 2 by means of nipples 3. The downtake headers 2 are connected to the uptake headers 4 by means of a bank of inclined tubes 5. One or more rows of inclined tubes 6 parallel to the tubes 5 connect corresponding downtake and uptake headers in the well known manner so that a detailed illustration or description of the same is not necessary for an understanding of the present invention. An intermediate superheater 7 is located between the tubes 5 and 6 and may be connected to the steam and water drum 1 in the usual manner. Baffles 8 and 9 extending across the tubes 5, direct the hot products of combustion from the furnace across these tubes in a plurality of passes as indicated by the curved arrows.

Rows of circulating tubes 10 connect the upper ends of the uptake headers 4 to a row of vertically disposed separator boxes or headers 11 at points intermediate their ends. The headers 11 are located between the headers 4 and the steam and water drum 1. A roof 12 is located above the circulating tubes 10. Rows of tubes 13 connect the upper portions of the headers 11 with the steam space of the steam and water drum 1, and rows of tubes 14 connect the lower portion of the headers 11 with the upper portions of the headers 2. The tubes 14 are inclined downwardly to drain water from the headers 11 to the headers 2.

A baffle 15 extends along the upper row of tubes 6 from the superheater 7 to the upper portions of downtake headers 16, the upper ends of which are connected by nipples 17 to

the lower ends of the headers 2. A baffle 18 is located along the inner side of the nipples 17.

The operation is as follows: Steam is generated in the usual way in the inclined tubes 5 and 6 and a mixture of steam and water passes through the upper portions of the headers 4 into the circulating tubes 10 and thence into the separator boxes or headers 11, the steam rising to the upper portions of these headers and thence passing through the tubes 13 into the steam and water drum 1, while the water passes to the lower portions of the headers 11, and thence through the tubes 14 into the upper portions of the headers 2, where it joins water passing downwardly through the nipples 3 into the headers 2. The hot gases flow in three passes across the tubes 5 and thence across the tubes 14 and 13 into the stack.

In the modification shown in Fig. 3, the baffle 18 is omitted in front of the nipples 17 and the hot gases pass in two passes flowing around the upper end of the baffle 8' across the tubes 5 and then pass out between the nipples 17. A baffle 19 is provided to prevent the hot gases from passing between the headers 11 and steam and water drum 1. This baffle may be located, for example, either along the upper row of tubes 14 or below the lower row of these tubes, the latter arrangement being illustrated in Fig. 3.

I claim:

1. In a steam boiler, a row of adjacent uptake headers; a row of adjacent downtake headers; a bank of steam generating tubes connecting the headers; a cross drum at the downtake header end of the boiler; a row of upright and independent steam and water separation headers located between the uptake headers and the drum at a position nearer the drum; connections discharging steam from the top parts of the separation headers into the steam space of the drum; connections discharging water from the lower parts of the separation headers into the boiler below its water level; and long circulators extending from the tops of the uptake headers into intermediate portions of the separation headers and connected thereto; the circulators,

separation headers, and drum acting to effect a three stage steam and water separation in which a substantial amount of such separation is effected by the circulators before they discharge into the separation headers, said connections being the only discharge connections from the separation headers to the drum and the boiler.

2. A cross drum steam boiler of the sectional header type comprising a plurality of adjacent uptake headers, a plurality of adjacent downtake headers, horizontally inclined steam generating tubes connecting the headers, a plurality of nipples directly connecting the water space of the drum and the downtake headers, a plurality of adjacent and separate upwardly extending separation headers disposed adjacent the drum and over the generating tubes, steam and water circulator tubes extending horizontally from the uptake headers for a distance greater than one half of the horizontal distance between the uptake and downtake headers and connected to intermediate portions of the separation headers, steam connections between the upper portions of the separation headers and the steam space of the drum, and connections discharging water from the lower parts of the separation headers into the boiler below its water level, the circulators being long enough and large enough to effect a substantial amount of steam and water separation, said connections being the only discharge connections from the separation headers to the drum and the boiler.

3. A cross-drum steam boiler comprising, in combination, a single horizontally disposed steam and water drum, a row of separate downtake headers connected to the water space of the drum, a row of separate uptake headers, steam generating tubes connecting the rows of headers, a row of independent upright separation headers extending above the water level of the drum and located adjacent the drum, connections discharging steam from the upper parts of the separation headers into the steam space of the drum, water connections leading downwardly from the lower parts of the separation headers into the boiler below its water level, circulators extending from the upper parts of the uptake headers and discharging into intermediate parts of the separation headers, and means maintaining the water connections out of contact with moving furnace gases, the circulators producing a substantial amount of steam and water separation, said connections being the only discharge connections from the separation headers to the drum and the boiler.

4. In a steam boiler, a row of adjacent uptake headers; a cross drum acting as a steam and water drum at the downtake header end of the boiler; long circulators leading from the top portions of the uptake headers

toward the drum; a row of independent and tubular steam and water separation parts each having an inlet at one side connected to the end of a circulator; said tubular parts having upper steam outlets and lower water outlets on their sides opposite the sides having the inlets connected to the circulators with the water outlets positioned at levels below those of the inlets connected to the circulators, connections discharging steam from the outlets of said parts into the steam space of the drum; and connections discharging the water from the lower outlets of said parts into the boiler below its water level; the circulators, said tubular separation parts, and the drum acting to effect a three stage steam and water separation in which a substantial amount of such separation is effected by the circulators before they discharge into the tubular separation parts, said connections being the only discharge connections from the separation parts to the drum and the boiler.
